UNITED STATES PATENT OFFICE

ALEXANDER G. CAMERON, OF WINNIPEG, MANITOBA, CANADA, ASSIGNOR
OF ONE-HALF TO FREDERICK JOHN IRWIN, OF WINNIPEG, CANADA.

WIRE-SPRING FABRIC.

No. 857,156.

Specification of Letters Patent.

Patented June 18, 1907.

Application filed June 1, 1906. Serial No. 319,742.

To all whom it may concern:

Be it known that I, ALEXANDER G. CAMERON, of the city of Winnipeg, in the Province of Manitoba, Canada, builder, have invented certain new and useful Improvements in Wire-Spring Fabric, of which the following is the specification.

My invention relates to improvements in wire spring fabric, more especially that adapted for the construction of bed springs and the like, and the object of the invention is to devise a simple, strong and durable construction of fabric, and it consists essentially of a series of inter-looped, locked strands of wire designed to be supported in a form all arranged and constructed as hereinafter more especially described.

Figure 1, is a perspective view of several of the strands looped together and also showing a method of securing the adjoining outstanding ends. Fig. 2, is a perspective view of a single looped strand showing a modification of that used in Fig. 1. Fig. 3, is a side view of the means employed for fastening the adjoining ends previous to securing permanently. Fig. 4, is a front view of the joint as in Fig. 3. Fig. 5, is a side view of the permanent joint formed at the ends.

In the drawings like letters of reference indicate corresponding parts in each figure.

A, is an individual length of resilient wire bent forwardly and backwardly upon itself in a simple saw tooth wave form forming opposing loops, B C respectively, staggered, 35 relatively, the one to the other. The uppermost series of loops B are simply plain bends in the wire, the loop remaining in the plane of the wiring forming the same. The lower series of loops C are formed by turning the 40 simple loop into a plane at right angles to the plane of the upper loops and at the same time bending the outstanding ends toward each other, forming a spring locking, receiv-

ing recess. In forming the loops B it is to be understood that they are formed alternately 45 by a right and left hand turn of the wire.

In forming my fabric, a series of such bent wires are joined the one to the other; the simple loop B being constrained within the loops C. The opposing outstanding ends of 50 an interlooped set are fastened by means of a ferrule D, through the side of which is an opening designed to receive the ends D¹, D², of the said wires. In making the joints the wires are inserted in the ferrule D and it is 55 flattened, thus turning the ends D¹, D², backwardly on themselves as clearly shown in Fig. 5. Although I prefer to use this joint, I wish 60 it to be understood that the simple hooked joint may be used and also that the individual 65 lengths of wire may be looped as shown in Fig. 2; the lower loops C of which are formed similarly to that C, Fig. 1, save that they are all formed by means of right hand turns of the wire.

It will be seen that I have invented a particularly, simple, cheap and durable fabric, which on account of its simplicity of formation and stability should prove itself invaluable in filling the requirements of such a 70 fabric.

What I claim as my invention is:

As a new article of manufacture, a fabric composed of a series of individual lengths of wire inter-looped and securely inter-locking 75 the one in the other, and means for fastening the outstanding ends of the inter-looped set, comprising a ferrule having an opening in the sides thereof to receive the said ends and designed to be flattened bending the ends upwardly and securing them therein as and for 8c the purpose specified.

ALEXANDER G. CAMERON.
